CHARLES H. AYER, FRANKLIN J. HOLE, AND RALPH E. OLNEY, OF MOUNT CLEMENS, MICHIGAN.

ADJUSTABLE MIRROR-SUPPORT.

No. 820,466

Specification of Letters Patent.

Patented May 15, 1906.

Application filed November 23, 1905. Serial No. 288,646.

To all whom it may concern:

Be it known that we, CHARLES H. AYER, FRANKLIN J. HOLE, and RALPH E. OLNEY, citizens of the United States of America, residing at Mount Clemens, in the county of Macomb and State of Michigan, have invented certain new and useful Improvements in Adjustable Mirror-Supports, of which the following is a specification, reference being had

thereto to the accompanying drawings.

This invention particularly relates to toilet-mirrors which are supported between standards upon articles of furniture, such as toilet-bureaus, and which permit of moving the mirror bodily out from between the supports and to be turned laterally and inclined at various angles in any position into which it may be moved.

The invention consists in the novel construction of the supporting-fixtures, involving an improvement in the means for hinging them to the supporting-standards of the mirror and also in providing certain stops to limit the movement of the fixtures to prevent injury to the furniture or to the wall against which it is standing, all as more fully hereinafter described, and shown in the accompanying drawings, in which—

Figure 1 is a rear elevation of a toilet-mirror provided with our improved mirror-support. Fig. 2 is a detached perspective view of the universal-hinge connection between the mirror-support and the mirror-frame. Fig. 3 is a detached perspective view of the adjustable bracket-support. Fig. 4 is a partial rear elevation showing a modified form of bracket and bracket-support.

In the drawings, A represents the vertical standards attached to the top of a toilet-bureau, and B is a toilet-mirror supported thereon by a pair of fixtures C, which are duplicates of each other and form the subject-matter of this invention. Each fixture comprises a bracket member D, provided with aligned pivots at top and bottom and with means for pivotally securing it in position on the standard to swing in a vertical plane. To this end the upper pivot is provided with a fixed bearing E, and the lower pivot has an adjustable bearing F, which consists of a plate a, having means for securing it to the back of the standard, and an outrigger-arm b, slidably adjustable thereon and forming a step e for the lower pivot of the bracket, all

so arranged that the lower pivot is laterally 55 adjustable to admit of the use of our fixtures on furniture of artistic design—as, for instance, shown in the drawings, wherein neither the mirror nor the standards have the conventional straight vertical outlines. As shown 60 in Fig. 3, the arm b is provided with stops d e, so positioned in relation to the bracket that the stop d limits its rear movement to prevent it from striking against the wall against which the bureau stands, while the other stop 65 e limits its forward movement to prevent it from striking the standards upon the inside. Upon the swinging end of the bracket is pivotally secured an arm G, so as to swing in a horizontal plane. It is adapted to fold and 70 rest on top of the bracket in the normal position of the mirror. To the end of this arm the mirror-frame is secured by means of a universally-adjustable hinge connection comprising the plate H, which is secured to the 75 back of the mirror-frame, and the link I, which is formed with two ears, one of which is pivotally secured between the forked ends of the plate H and the other between the forked ends of the arm G, the pivotal connections being 80 respectively made by a vertical bolt f and a horizontal clamping thumb-screw g, which permit of applying suitable friction to the hinge-joints.

In Fig. 4 we show a slight modification, in 85 which the bracket has ears for hinge connection with its supports by means of bolts h, which form removable hinge-pins for the bracket, and the outrigger b is screw-threaded into the plate a for the purpose of adjustability. As shown in the drawings, the arm E folds on top of the bracket, so that when the mirror is in its normal rearward position the arm will bear at its free end on the parts below, and thus relieve the hinges of a portion 95 of the weight of the mirror.

It will be seen that the construction herein shown and described forms a simple and inexpensive adjustable mirror-support which is easily applied and which is applicable to a 100 greater variety of designs in toilet-bureaus than those in present use.

What we claim as our invention is—

1. A mirror-support for bureaus and the like, comprising a pair of like fixtures, each 105 comprising a bracket, an arm hinged to the bracket, a universal-hinge connection between the arm and the mirror-frame, and supports

hingedly connecting the bracket at its upper and lower ends with one of the supporting standards of the mirror, the lower support being laterally adjustable.

- 5 2. A mirror-support for bureaus and the like comprising a pair of like fixtures, each comprising a bracket, an arm hinged to the bracket and adapted to fold on top of the bracket, a universal-hinge connection between the arm and the mirror-frame and supports hingedly connecting the bracket at its upper and lower ends with one of the sup-

porting-standards of the mirror, the lower support being laterally adjustable and provided with stops to limit the swing of the bracket thereon.

15 In testimony whereof we affix our signatures in presence of two witnesses.

CHARLES H. AYER.
FRANKLIN J. HOLE.
RALPH E. OLNEY.
